UNITED STATES PATENT OFFICE.

HAZEL RUSH, OF CHARLOTTE, NORTH CAROLINA.

DESIGN FOR A TOY.

• 54,456.

Specification for Design.

Patented Feb. 10, 1920.

Application filed August 20, 1918. Serial No. 250,750. Term of patent 3½ years.

To all whom it may concern:

Be it known that I, HAZEL RUSH, a citizen of the United States, residing at Charlotte, in the county of Mecklenburg and State of North Carolina, have invented a new, original, and ornamental Design for Toys, of which the following is a specification, reference being had to the accompanying drawing, forming part thereof.

The figure is an elevation of a toy showing my new design.

I claim:

The ornamental design for a toy, as shown.

HAZEL RUSH.
